UNITED STATES PATENT OFFICE.

WILLIAM JOHN GRAY, OF JEANNETTE, PENNSYLVANIA.

DESIGN FOR A LAMP-SHADE.

40,379.

Specification for Design.

Patented Nov. 30, 1909.

Application filed August 12, 1909. Serial No. 512,624. Term of patent 3½ years.

To all whom it may concern:

Be it known that I, WILLIAM JOHN GRAY, a citizen of the United States, residing at Jeannette, in the county of Westmoreland and State of Pennsylvania, have invented a certain new, original, and ornamental Design for a Lamp-Shade, of which the following is the specification, reference being had to the accompanying drawing, forming part thereof.

The figure is a perspective view illustrating my new design.

I claim:

The ornamental design for a lamp shade, as shown.

WILLIAM JOHN GRAY.
